DESIGN FOR AN OUTBOARD MOTOR

Finn T. Irgens, Wauwatosa, Wis., assignor to
Outboard Motors Corporation, Milwaukee, Wis.,
a corporation of Michigan

Application January 15, 1934, Serial No. 50,406

Term of patent 14 years

To all whom it may concern:

Be it known that I, FINN T. IRGENS, a citizen
of the United States, residing at Wauwatosa, in
the county of Milwaukee and State of Wisconsin,
have invented a new, original, and ornamental
Design for an Outboard Motor, of which the fol-
lowing is a specification, reference being had to
the accompanying drawing, forming part thereof.

In the drawing:

Figure 1 is a side elevation of an outboard mo-
tor embodying the invention.

Figure 2 is a plan view thereof.

The lower unit, being of conventional design,
is shown in light lines. The power head, is shown
in heavy lines.

I claim:

The ornamental design for an outboard motor
having a power head of the design shown and
described.

FINN T. IRGENS.
